UNITED STATES PATENT OFFICE.

FREDERICK WALLACE, OF EDEN, NEW YORK.

TONGUE-SUPPORTING MEANS FOR WAGONS.

1,405,365.

Specification of Letters Patent. Patented Jan. 31, 1922.

Application filed April 2, 1920. Serial No. 370,794.

To all whom it may concern:

Be it known that I, FREDERICK WALLACE, a citizen of the United States, residing at Eden, in the county of Erie and State of New York, have invented new and useful Improvements in Tongue-Supporting Means for Wagons, of which the following is a specification.

This invention relates to tongue supporting means for lumber wagons and the principal object of the invention is to make the device adjustable so as to fit different sizes of wagons.

Another object of the invention is to provide a socket on the device for receiving the tongue.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a plan view of the front part 30 of a wagon supplied with my invention.

Figure 2 is a bottom plan view of the device itself.

Figure 3 is a cross section on line 3—3 of Figure 2.

Figure 4 is a section on line 4—4 of Figure 2.

In these views 1 indicates the front part of a wagon which includes the hounds 2. The means for connecting the tongue 3 to said hounds comprises a member 4 having a tongue receiving socket 5 at its forward end and its rear part made in the form of a plate 6 which is provided with a central web 7 extending downwardly from the central part of the bottom of the plate. The sides of the plate are provided with wings 8 which have slots 9 therein for receiving bolts. The socket is provided with holes 10 in its top and bottom for receiving a bolt 11, which holds the tongue in said socket.

This bolt also passes through the arm 12 which is bolted to the member. The usual doubletree fits between said arm and the

upper face of the member and is pivoted on the bolt. 55

Hounds engaging members 13, formed of angle-shape and each provided with a pair of arms 14, are adjustably connected with said member by means of the bolts 15 passing through the holes 9 in the wings and 60 through slots 16 in said arms. The bolts pass through washers 17, which are each provided with a roughened face to engage a roughened part on each arm 14, adjacent the slots. As shown one of the arms 14 65 is longer than the other arm so that the member 13 is held at an angle to the rest of the device so as to properly engage the forward parts of the hounds. A long bolt 18 passes through the hounds, through the 70 members 13 and through the web 7 on the underside of the plate 6.

It will thus be seen that the device can be made to fit different sizes of wagons by adjusting the members 13 on the central 75 part of the device to fit the hounds of the wagon. The tongue is held in the socket 5 and can be easily renewed by withdrawing the bolt 11 which passes through said socket.

It is thought from the foregoing description that the advantages and novel features 80 of my invention will be readily apparent.

I desire it to be understood that I may make changes in the construction and in the combination and arrangement of the 85 several parts, provided that such changes fall within the scope of the appended claim.

What I claim is:—

In combination with a wagon, tongue supporting means therefor comprising a member 90 having a socket at one end for receiving the tongue and its remaining end made in the form of a plate, a central web provided on said plate and extending downwardly from the central part of the bottom thereof, wings provided on the sides of the plate and having slots therein for receiving bolts, means for holding the tongue in the socket, angle members each having a pair of arms 95 having slots therein, bolts passing through 100 the openings in the wings and said slots for adjustably holding said angle members in place.

In testimony whereof I affix my signature.

FREDERICK WALLACE.
